UNITED STATES PATENT OFFICE.

ELWOOD C. PHILLIPS, OF GARDEN CITY, KANSAS, ASSIGNOR TO THE PHILLIPS ECONOMICAL CABLE GRIP CONSTRUCTION COMPANY, OF CHICAGO, ILLINOIS.

CONDUIT FOR CABLE RAILWAYS.

SPECIFICATION forming part of Letters Patent No. 400,482, dated April 2, 1889.

Application filed December 26, 1888. Serial No. 294,705. (No model.)

To all whom it may concern:

Be it known that I, ELWOOD C. PHILLIPS, a citizen of the United States, residing at Garden City, in the county of Finney and State 5 of Kansas, have invented certain new and useful Improvements in Conduits for Cable Railways; and I do hereby declare the following to be a full, clear, and exact description of the invention, such as will enable others skilled 10 in the art to which it appertains to make and use the same.

This invention relates to conduits for cable railways provided with a dirt receptacle or pocket under a top opening for the grip, the 15 main chamber of the conduit not being directly below said opening.

The said invention consists in such a conduit having an inwardly-extending wall below said opening, the hollow interior of the 20 conduit being enlarged on one side above said wall to form a pocket, into which said wall directs the earth and rubbish falling through said opening.

The said invention also consists in certain 25 additional improvements in construction, hereinafter set forth and claimed.

In the accompanying drawings, Figure 1 represents a vertical cross-section of one form of my conduit, and Fig. 2 represents a similar 30 view of another form thereof.

In either case each section of the conduit is made in a single casting, the opening *a* for the shank of the cable-grip being in the top thereof on one side of the middle line of the 35 space *A*, in which is the cable. This space fills the greater part of the interior of the casting; but the upper part of it communicates on one side with a pocket, *B*, formed in the upper part of said casting and extending out 40 sidewise beyond the line of space *A*. The inner part of this pocket is above a part of said space, but is separated therefrom by a wall, *C*, cast with said conduit, which extends obliquely upward and inward from the side of 45 the casing, preferably in a curved line, forming a part of the bottom of said pocket and the inner wall thereof. The opening *a* is directly above this wall *C* or the bottom of the pocket at its base, so that the earth and rub-

bish falling through the opening *a* will go into 50 the pocket *B* and not into the space *A*, constituting the body of the conduit. Nevertheless a slight inclination of the shank of the gripping devices will enable it to avoid said wall *C*. There is thus no need for the awkward bending nearly at right angles, which has been necessary with conduits opening at 55 the side. As each section of the entire conduit is in one piece, the wall *C* being cast therewith, strength and simplicity are attained in the highest degree.

As shown in Fig. 2, I sometimes construct the opening *a* with a downward flare to insure the passage through it of earth and rubbish, the said opening being also faced with 65 steel plates *D* as a protection against wear or other injury to the cast metal at the sides of said conduit. These plates are provided with outwardly-extending screw-threaded studs *d*, which pass through in the raised side walls, 70 *a'*, of said opening and act as bolts to hold said plates in place, being secured by nuts *f*. Fig. 2 also shows the conduit provided with wings *E*, cast therewith, extending to equal distances on each side of opening *a*, 75 and having near their ends flattened upper faces or tables, *F*, on which paving-blocks or other roadway material may be laid, or they may be used for supporting the rails of the car-track. Terminal shoulders *F'*, raised 80 above these tables, will hold said rails in position and aid in preventing the lateral displacement of any section of the conduit whatever may be placed thereon. The steel plates *D* are provided with horizontal top flanges, 85 *D'*, extending over the raised side walls, *a'*, of opening *a* to protect said walls and afford a broad surface. The wings *E* add symmetry to the appearance of the conduit seen from above. The raised side walls, *a'*, (shown in 90 both figures,) are useful in excluding from opening *a* the earth at the sides of them. For greater security against earth entering the space *A*, I extend the plate *D* downward, as shown in Fig. 1, to form a guide-lip, *H*, opposite the tip of wall *C*, said wall bending upward to a point, as shown.

I, Fig. 2, designates a pair of arms extend-

ing from the material of the conduit at the lower part of space A inward and upward toward each other, and having on their proximate ends bearings *i* for the shaft *j* of a 5 grooved roller, *J*, which supports the cable *K*. There are as many of such rollers as may be necessary to conveniently support said cable arranged at suitable intervals. These arms and rollers may of course be used with either 10 form of conduit which I have shown, or with any suitable form. This is also true of the steel plates *D*.

The conduit may be of wrought metal instead of cast metal; but its construction 15 would then be more difficult and expensive.

Having thus described my invention, what I claim as new, and desire to secure by Letters Patent, is—

1. A conduit for cable railways, having an 20 opening in the top for the shank of the cable-grip and a pocket in the upper part of the conduit below said opening for catching the earth and rubbish which fall through the latter and preventing them from descending to the 25 cable and the gripping devices, and the space for the latter being separated from said pocket by a wall inclining obliquely upward and also inwardly with regard to said space, substantially as set forth.

30 2. A conduit for cable railways, having the main space A for the cable and gripping devices, the pocket B in the upper part of said conduit, the curved wall C, extending obliquely between them and the opening *a* in the top

of said conduit above said wall, substantially 35 as set forth.

3. A conduit having an opening in its top and an inwardly-extending wall below said opening integral with said conduit, the hollow interior of said conduit being enlarged 40 on one side above said wall to form a pocket, into which said wall directs the earth and rubbish falling through said opening, substantially as set forth.

4. A conduit having an opening in its top, 45 a pocket for receiving the earth and rubbish which may fall through the same, and a downwardly-extending lip or corner on one side of said opening to aid in directing said earth or rubbish into said pocket, substantially as set forth.

5. A conduit having a main space, A, for the cable, a pocket, B, obliquely above the same, an opening, *a*, above said pocket, a wall, C, extending obliquely upward between 55 said pocket and the main space of said conduit, and a lip extending downward on the same side of opening *a*, in order that said lip and wall may combine to direct dirt and rubbish into said pocket, substantially as set 60 forth.

In testimony whereof I affix my signature in presence of two witnesses.

ELWOOD C. PHILLIPS.
